CLAIM

The ornamental design for a latch for attaching an animal feeding pan to a gate member as shown and described.

DESCRIPTION

FIG. 1 is a perspective view of a latch in a locked position for attaching an animal feeding pen to a gate member showing my new design;

FIG. 2 is a front view thereof in a locked position;

FIG. 3 is a front view thereof in an unlocked position;

FIG. 4 is a top view thereof in an unlocked position;

FIG. 5 is a perspective view thereof in an unlocked position;

FIG. 6 is a top view thereof in a locked position;

FIG. 7 is a bottom view thereof in a locked position;

FIG. 8 is a bottom view thereof in an unlocked position;

FIG. 9 is an end view thereof in a locked position, the opposite end view being a mirror image; and,

FIG. 10 is an end view thereof in an unlocked position, the opposite end view being a mirror image.

The animal feeding pan and gate member shown in broken lines in FIGS. 1, 5, 9 & 10 are for environmental purposes and form no part of the claimed design.

1 Claim, 10 Drawing Sheets
